US0D1061494S

(12) **United States Design Patent** (10) **Patent No.:** **US D1,061,494 S**
(45) **Date of Patent:** **** Feb. 11, 2025**

(54) **CARD CASE FOR PHONE**

(71) Applicant: **Shenzhen Mincho Technology Co., Ltd**, Shenzhen (CN)

(72) Inventor: **Ming Liu**, Wuhan (CN)

(73) Assignee: **Shenzhen Mincho Technology Co., Ltd**, Shenzhen (CN)

(**) Term: **15 Years**

(21) Appl. No.: **29/965,377**

(22) Filed: **Sep. 27, 2024**

(30) **Foreign Application Priority Data**

May 31, 2024 (CN) 202430331184.4

(51) **LOC (15) Cl.** **14-03**

(52) **U.S. Cl.**

USPC **D14/250**; D14/249

(58) **Field of Classification Search**

USPC ..... D14/250, 253, 251, 138 R, 252, 426

CPC H04M 1/185; H04M 1/04; H04M 1/0202;

H04M 1/0279; H04M 1/0249

See application file for complete search history.

(57) **CLAIM**

The ornamental design for a card case for phone, as shown and described.

DESCRIPTION

FIG. 1 is a first perspective view of a card case for phone showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of the card case for phone in an alternate configuration;

FIG. 10 is another perspective view thereof;

FIG. 11 is a perspective view of the card case for phone shown with environment;

FIG. 12 is another perspective view of the card case for phone shown with environment;

FIG. 13 is another perspective view thereof;

FIG. 14 is another perspective view thereof;

FIG. 15 is another perspective view thereof; and,

FIG. 16 is another perspective view thereof.

The broken line showing of portions of the article and environmental structure forms no part of the claimed design.

1 Claim, 16 Drawing Sheets
